(57) **CLAIM**

The ornamental design for a container for cosmetic material as shown and described.

DESCRIPTION

FIG. 1 is a top perspective view of a container for cosmetic material showing my new design;

FIG. 2 is a bottom perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is an enlarged left side view of the container for cosmetic material;

FIG. 10 is an enlarged view in a portion of the container for cosmetic material shown within the area designated as 10 in FIG. 6 thereof;

FIG. 11 is an enlarged view of a portion of the container for cosmetic material shown within the area designated as 11 in FIG. 1 thereof;

FIG. 12 is an enlarged view of a portion of the container for cosmetic material shown within the area designated as 12 in FIG. 2 thereof; and,

FIG. 13 is a cross-sectional view of the container for cosmetic material taken in the direction of line 13-13 in FIG. 10.

The broken lines show portions of the container for cosmetic material that form no part of the claimed design.

The dot-dashed lines shown in FIGS. 2, 6, 8, 9, 10, 11, and 12 depict the boundary of the claim and form no part of the claimed design.

The dot-dot-dashed lines surrounding portions of the container for cosmetic material in FIGS. 1, 2, and 6 and
